CATCHUP DISPENSER

John C. Lowe, Jr., Youngwood, Pa.

Application July 19, 1946, Serial No. 684,651

1 Claim. (Cl. 222—322)

1

This invention relates to dispensing devices in the form of a closure and extruder for bottles containing ketchup and other liquid and semi-liquid substances.

As is well known, after a fresh bottle of ketchup has been uncapped and subject to the atmosphere, it quickly clogs in the neck of the bottle and frequently considerable exertion is necessary in order to shake the contents from the bottle.

The principal object of the present invention is to provide an auxiliary closure and dispenser adapted to be applied to such bottles as contain ketchup, so as to exclude air from the bottle after it has been initially opened, to preclude the hardening of the ketchup in the neck of the bottle and to also facilitate the extraction of the ketchup from the bottle in the portions desired.

Another object of the invention is to provide a closure and dispenser for ketchup bottles which can be quickly and accurately applied to a ketchup bottle neck without any modification of the bottle proper, and which can be used over and over again as fresh ketchup bottles are opened.

These and various other objects and advantages of the invention will become apparent to the reader of the following description.

In the drawing:

Figure 1 is a fragmentary side elevational view of the device applied to a bottle neck;

Figure 2 is a fragmentary detailed sectional view taken substantially on line 2—2 of Figure 1;

Figure 3 is a horizontal sectional view taken on line 3—3 of Figure 2;

Figure 4 is a side elevational view of the device detached from the bottle.

Referring to the drawing, numeral 5 generally refers to a ketchup bottle, or in fact, a bottle containing any substance that has a tendency to solidify or harden when subjected to the atmosphere. This type of bottle 5 generally has a head portion 6, which in merging with the neck portion 7 defines a shoulder 8.

The present invention is generally referred to by numeral 9 and consists of a knob 10 having an elongated depending stem 11, slideable through an opening in the upper portion of a downwardly flaring hood 12, the lower end of the stem 11 carrying a ketchup pusher disc 13, between which and the upper interior of the hood 12 a coiled compression spring 14 is interposed, the spring 14 being convoluted about the stem 11.

The hood 12 has an outstanding flange 15 defining a cover for the upper end of the bottle 55

neck, this flange 15 being cut off on the chordal line 16, the flange 15 having its circular formation continued by the presence of a section 17 carried by a leg 18 depending from the knob 10 and which, when the closure is properly seated, fits in an opening in the side wall of the hood 12. The section 17 and the flange 15 have rubber or other resilient pieces 19, 20 respectively, secured against their undersides and bearing against the head 6 of the bottle to exclude air from the interior of the bottle.

An outstanding and depending leg 21 projects from the flange 15 and carries a spring clip 22 at its lower end for embracing the neck of the bottle at a point just under the shoulder 8. This clip snugly hugs the neck of the bottle and preferably bears against the shoulder 8, so that upon lifting the knob 10, the device cannot become detached from the bottle.

20 In the use and operation of the device, the bottle is first tilted so that ketchup will run into the neck portion thereof, after which the knob 10 is pulled outwardly to the dotted line position shown in Figure 2, which will unseat

25 the closure section 17, as the pusher disc 13 forces the ketchup in the neck, out through the opening left by the section 17, while the spring 14 compresses itself in the dome 12, allowing the pusher disc 13 to be pulled very close to the closure flange 15, extruding practically all of the ketchup in the neck, if that much is desired. As much ketchup from the neck of the bottle as is desired can be extruded by regulating the extent of pull of the knob 10.

30 35 The clip 22 which is forced over the head 6 in the original placement of the device on the bottle will snugly hug the neck of the bottle and prevent accidental displacement of the device therefrom.

40 The device can be constructed of inexpensive materials and can be used on successive bottles of ketchup and over a considerable period of time, due to its durable and substantially fool-proof construction.

45 While the foregoing description sets forth the invention in specific terms, it is to be understood that numerous changes in the shape, size and materials may be resorted to without departing from the spirit and scope of the invention as claimed hereinafter.

Having described the invention, what is claimed as new is:

46 A dispensing closure for bottles having a shouldered neck comprising a lid for disposition over the top of the bottle neck, means for dispensing

the contents of the bottle through said lid, said lid being provided with a depending leg extending downwardly along the neck of the bottle, and a spring clamp to which the leg is secured, said spring clamp being adapted to embrace the neck portion of the bottle under the shoulder thereof, said means for dispensing the contents of the bottle consisting of a slide member movable through the lid, said lid having a sectional portion attached to the slide member and adapted to be lifted by said slide member to define an opening through which the contents of the bottle can be poured.
